UNITED STATES PATENT OFFICE.

JOHN B. SEMPLE, OF SEWICKLEY, PENNSYLVANIA.

PROJECTILE.

1,105,848.

Specification of Letters Patent. Patented Aug. 4, 1914.

Application filed June 6, 1913. Serial No. 772,143.

To all whom it may concern:

Be it known that I, JOHN B. SEMPLE, residing at Sewickley, in the county of Allegheny and State of Pennsylvania, a citizen of the United States, have invented or discovered certain new and useful Improvements in Projectiles, of which improvements the following is a specification.

My invention relates to improvements in fuses for the bursting charges of explosive projectiles and its object is to afford a fuse selective in its delay action in this respect:—that, in case the projectile strikes a light obstruction (such as a thin plate), the fuse 10 will operate without delay, to explode the bursting charge; but, in case the projectile strikes a heavy obstruction (such as a thick armor plate), the operation of the fuse will be delayed—the object in view in either case 15 is that the projectile shall explode immediately after it has penetrated the plate.

A fuse embodying my present invention is illustrated in the accompanying drawings, in which—

Figure 1 shows in longitudinal section a projectile with the fuse in place therein, and Fig. 2 is a similar view and on larger scale of the fuse detached from the projectile. A certain detail of structure permitting of 25 modification, is shown in alternative form in these two figures.

Corresponding parts are numbered to correspond.

The projectile itself is indicated by the 30 numeral 1; and, since my invention has to do with a fuse for a bursting charge, the projectile is necessarily one provided with a cavity containing a bursting charge. This cavity is indicated by the numeral 2.

Secured in the body of the projectile, and 35 preferably in its base is the fuse. It consists, essentially, of a stock or block, 3, carrying in a suitable chamber an ignition charge, 4, and means for firing said ignition charge, 40 under proper conditions. To this end, the chamber containing the ignition charge is arranged at the anterior end of the structure and is closed rearwardly by a cap-socket, 5, provided with a percussion-cap, 6, and with 45 a duct, 7, leading from said cap to the chamber containing the ignition charge. Rearward of said cap socket 5 is a firing-plunger 8, and these parts are so arranged and assembled that normally the firing-plunger is 50 spaced at an interval from the cap socket, but that when the projectile strikes, the im-

pact will cause the plunger to traverse the intervening space and, delivering a blow, to fire the ignition cap, thus firing in turn the ignition charge and eventually the 60 burster charge in chamber 2.

A convenient arrangement is that shown in the drawings. The firing-plunger is placed in a chamber rearward of the cap socket and is movable therein in the direction of the length of the projectile; the firing-plunger is held retracted by the spring 65 9, whose strength will be understood to be adapted to the end in view.

Regarding the fuse thus far described in 70 its general characters, it will be seen to be a fuse which is fired by the force of impact, and it is with such a fuse, generally, that my present invention has to do, regardless of its more specific construction.

The ignition chamber, and the means for firing the charge within it (which, in this instance consist essentially of the cap socket with its cap and the hammer-block) are 75 borne on the stock 3 in any suitable manner (as by being contained in a casing, 10) and the union by which they are borne on the stock—and herein lies the essential feature of my present invention—is a union which under certain conditions of service may be 80 broken. The particular form of union may be varied, and I limit my invention to no specific form of union as such; specifying only that it shall be secure under all conditions of handling and service, short of the 85 relatively great shock produced when a projectile carrying it strikes such an obstruction as an armor plate, but that under such a shock it shall be frangible. In Fig. 1 the union is shown to be accomplished in the 90 crimping of the posterior rim 11 of casing 10 upon a rearwardly tapering neck 12 formed on block 3, and in Fig. 2 I have shown a screw-thread connection 13, relatively weak because of the shallowness of 95 the threads and the small number of turns; but, as I have said, any union whose security may be limited to a breaking-strain which may be predetermined with sufficient accuracy will serve the purpose.

The selective effect in operation is this: In 100 case a projectile provided with this fuse of my invention, after being fired from a gun strikes a mark or target whose resistance to penetration is less than the certain critical 110 amount—a target, be it understood, of relatively light plate—the union of the fuse to

its stock will hold secure, the fuse will operate at once, and explosion will follow. But if the projectile in its flight strikes a mark or target whose resistance to penetration is 5 greater than the critical amount—that is to say a heavy armor plate—the union of the fuse case to the stock will, under the greater shock, be torn apart, and the operation of the fuse will be delayed; for the whole fuse 10 structure will set forward within chamber 2 until its progress is arrested by the body of explosive material within the chamber, whereupon the fuse will operate, and explosion ensue. It has been proved by 15 actual firing that, notwithstanding the difference between the resistance offered to the movement of the firing plunger (the tension of spring 9), and the resistance to forward movement of the case 10 (the weak threads 20 of the block 3 or equivalent means), the cap socket containing the cap and the firing plunger with its firing point move forward together, and the interval between the cap and the point is not closed, until the case 10 25 brings up solidly against the compressed bursting charge of the shell. The delay in action thus provided for is designed to afford time—minute but adequate—for the projectile to penetrate (if it be able) the 30 armor which it has struck, to the end that explosion may occur after penetration.

I have in Fig. 1 shown the fuse member extending forward from its stock into the chamber 2. It will be understood that this 35 chamber is otherwise filled with explosive material. Ordinarily this mass of explosive material will be sufficiently yielding, and will not fill the chamber so compactly, but that the forward and operative end of the 40 fuse, when once it has broken from the stock, will drive forward an appreciable distance into the body of explosive material, before being stopped and (by stopping) fired. If the explosive material employed be of a

densely compressed nature, a sufficient space 40 may be left when the material is being packed in the chamber 2, to permit of the forward drive of the severed fuse members under conditions described.

It will be understood that any arrangement of the fuse with relation to the chamber 2 is permissible, so long as the ignition of charge 4 will—whatever the position of the fuse—gain access to the body of explosive material in chamber 2. 50 55

As shown in the drawings, the forward end of the fuse is blunt-pointed, to adapt it to drive forward into the body of material in chamber 2. Vents 14 from the chamber which contains the ignition charge 4 to the 60 chamber 2 may be protected by a ring 15 of such nature as to allow the passage of the flash of the magazine charge 4.

It will be understood that the invention now described is applicable to a detonating 65 fuse, equally as well as to the ignition fuse shown, and this without change in the parts described as constituting the invention.

I claim herein as my invention:

1. A projectile fuse operated by impact 70 and attached to a projectile body by a union secure against light strain and destructible under heavy strain, substantially as described.

2. In a projectile, a fuse normally carried 75 by the projectile body and including a firing member movable in the fuse body on a sudden change in velocity, the union of the said fuse to said projectile body frangible on a sudden and greater change in velocity, 80 substantially as described.

In testimony whereof I have hereunto set my hand.

JOHN B. SEMPLE.
